[57] CLAIM

The ornamental design for an expansion port converter for notebook personal computer, as shown and described.

DESCRIPTION

FIG. 1 is a front, left side, top perspective view of an expansion port converter for notebook personal computer showing our new design in an operative position with a notebook personal computer and an expansion base being shown in broken lines for illustrative purposes only and forming no part of the claimed design;

FIG. 2 is a rear, left side, top perspective view thereof with a notebook personal computer being shown in broken lines for illustrative purposes only and forming no part of the claimed design;

FIG. 3 is a rear elevational view thereof;

FIG. 4 is a right side elevational view thereof;

FIG. 5 is a left side elevational view thereof;

FIG. 6 is a top plan view thereof;

FIG. 7 is a front, left side, top perspective view thereof;

FIG. 8 is a front elevational view thereof; and,

FIG. 9 is a bottom plan view thereof.
